UNITED STATES PATENT OFFICE

2,373,560

SOUND RECORDING METHOD AND APPARATUS

John M. Hanert, Wilmette, Ill., assignor to Hammon Instrument Company, Chicago, Ill., a corporation of Delaware

Application July 29, 1941, Serial No. 404,487

29 Claims. (Cl. 179—100.4)

My invention relates generally to sound producing, recording, and reproducing methods and apparatus, and more particularly to the provision of means and methods for introducing vibrato and similar effects in sounds, speech, and musical tones.

A vibrato effect, as in the voice and as in the tones of some musical instruments—notably the violin and Hawaiian guitar—is produced by a periodic variation in the pitch of the tone at a periodicity of approximately seven cycles per second, although the vibrato rate may be varied between five and ten cycles per second to obtain various effects. If the rate is less than five cycles per second or more than ten cycles per second, most musicians will consider the effect undesirable. The range of frequency variation in the pitch of the tone necessary to obtain a musically acceptable vibrato effect is from 0.2% to 6.0% of the frequency of the tone; that is, a periodic shift in frequency from 0.1%—3.0% above to 0.1%—3.0% below the nominal frequency of the tone. For example, for the note A=440 C. P. S., the frequency variation might be between the frequencies of 439.6 C. P. S. and 440.4 C. P. S. to obtain a very small or "narrow" vibrato effect, while to obtain a large or "wide" vibrato effect, the frequency variation might be between 426.8 C. P. S. and 453.2 C. P. S. These exemplary limits are not exact, since the listener's determination of what constitutes a pleasing vibrato effect depends upon his musical perception and the mood of the musical selection being rendered.

On the average, a pleasing vibrato effect may be assumed to be obtained by a 6% frequency modulation of the tone at an average periodicity of 7 C. P. S. The frequency modulation should preferably be applied gradually.

Most musical instruments are incapable of producing tones incorporating the vibrato effect. This is to be expected if the instrument is to be easily played on some given pitch. That is, the musical tone generators usually take the form of some stable tuned system, such as a piano string, reed, pipe, and the like. In the case of the piano, the frequencies of vibration of the strings are extremely constant and the musician has no means for imparting a vibrato effect or of altering the tuning of the strings while playing. Other instruments of this class having no means for introducing vibrato are the chimes, xylophone, celeste, marimba, and harpsichord. Fretted instruments, such as the guitar, also present little opportunity for the vibrato effect because the frets more or less limit the number of frequencies

possible to the notes of the scale. Likewise, the woodwinds, orchestral reeds, and accordion produce very little vibrato.

The pipe organ, flute, and clarinet fall in a second class of instruments in which the vibrato effect is achieved only in conjunction with a tremulant or intensity modulation, the latter being usually considered monotonous by musicians. That is, the frequency of the pipe can be conveniently shifted only by reducing the wind pressure, which reduction, however, results in a relatively large diminution of sound apart from the frequency shift or vibrato effect.

Another effect, resembling the vibrato, is produced by simultaneously sounding several pipes which are purposely tuned flat and sharp of the correct pitch to produce a chorus effect. This is also the pleasing effect of several musicians playing a note simultaneously as compared to the note played by a single player.

The reason the vibrato and chorus effects are pleasant probably lies in the fact that more auditory nerves terminating at the basilar membrane of the ear are excited, each however to a lesser degree than in the case of a single loud tone devoid of vibrato and in which the energy is concentrated on but a relatively few frequencies resulting in but a few auditory nerves being violently excited. In other words, if the music as heard by the listener consists of a great many frequencies, such as provided by vibrato and ensemble tonalities, the ear is less easily fatigued. The many sounds of nature, such as the wind through trees and the sound of ocean waves are particularly pleasant and restful to listen to because of their great audibility, that is, they sound loud, but at the same time do not unduly penetrate or fatigue the ear. Consequently, music in general, becomes more pleasant to hear if a considerable degree of vibrato is introduced, which, however, should in no way change the musician's technique in playing standard instruments. In addition, the use of but a few instruments with vibrato added is often equivalent in musical appeal to many instruments sounding simultaneously without the benefit of the vibrato effect. (A small number of standard instruments with the vibrato effect added produces the same tonal warmth as a larger group of such instruments.)

The vibrato is a very important element in musical expression and its addition to the tonality at times of emotional climax adds greatly to the musical expressiveness. This is possibly due to the associative fact that the human voice, more or less naturally, has a pronounced vibrato when

the speaker or singer is expressing an emotion.

Another application of the vibrato consists in introducing it into poetic and dramatic readings to an extent greater than normally possible with the human voice. Thus, the reading of mystery stories and other exciting selections is greatly enhanced through addition of vibrato at times of emotional stress.

In general, the invention comprises making a record of the sound in which the vibrato is to be incorporated, picking up a signal from such record by a pickup which moves relative to the record at a speed varying at vibrato periodicity, amplifying this signal, and making a record of the amplified signal. The desired results may be obtained by a variety of slightly different methods and by the use of a considerable variety of different kinds of apparatus.

It is thus an object of my invention to provide an improved method and apparatus for incorporating a vibrato effect in recorded sounds.

A further object is to provide an improved phonographic method and apparatus for making sound records incorporating vibrato effects.

A further object is to provide an improved method and apparatus for photoelectrically recording sound modulated to produce a vibrato effect.

A further object is to provide an improved method and apparatus for making sound records.

A further object is to provide an improved method and apparatus for reproducing sound or music in a manner which introduces a vibrato effect.

A further object is to provide an improved means for readily controlling the width and periodicity of the vibrato to be introduced into a sound.

A further object is to provide an improved vibratory motor apparatus which may be easily adjusted as to amplitude and frequency of vibration.

A further object is to provide a method and apparatus, whereby a vibrato of continually varying periodicity may be introduced, so that the listener is not able to detect a definite vibrato rate.

Other objects will appear from the following description, reference being had to the accompanying drawings, in which:

Fig. 1 is a diagrammatic view of a preferred form of apparatus for performing the method, in which the vibrato is photoelectrically controlled;

Fig. 2 is a partially diagrammatic elevational view of a modified form of the apparatus used to practice the invention;

Figs. 3 and 4 are similar views of modified forms of the apparatus;

Fig. 5 is a wiring diagram of an adjustable oscillator for energizing the vibratory motor;

Fig. 15 is a diagrammatic view of modified forms of the apparatus employing a magnetized tape record.

Fig. 16 is a wiring diagram employing a relaxation oscillator for producing impulses at a vibrato frequency;

Fig. 17 is a schematic diagram of an additional form of apparatus for producing impulses at a vibrato frequency;

Fig. 18 is a schematic diagram of a modified recording apparatus in which the vibrato effect is introduced by the cutting head of the recording apparatus;

Fig. 19 is a diagrammatic view of a modified form of the invention, in which the vibrato may selectively be made more or less effective on the high or the low frequencies of the sound transmitted; and,

Fig. 20 is a schematic view of a modified form of the invention, in which the vibrato modulating frequency is manually introduced.

In Fig. 1, the apparatus for introducing the vibrato effect is illustrated as comprising a phonograph motor 30 mounted on a suitable base 31 and driving a turntable 32 at the customary speed. The turntable carries a record A, which is a recording of the music or sound into which the vibrato effect is to be introduced. A suitable pickup 34, which may be of the crystal or any other suitable sensitive type, is arranged for co-operation with the record A and is connected to an amplifier 36, the output of which is connected to the recording apparatus, which may be of any well known construction.

A monitoring speaker 40 is preferably connected in parallel with the recording apparatus so that the operator of the apparatus may listen to the sound as it is being recorded. The tone arm 42 carrying the pickup 34 is mounted upon a resilient support 44, which is preferably resilient in itself and is imbedded in a base 46 of sponge rubber or the like. The base 46 is carried by a bracket 48, which is mounted for oscillation on a bearing 50 carried by the base 31, this pivotal mounting of the bracket 48 being provided so that the tone arm may swing to follow the groove in the record.

A driver 52 is preferably in the form of an electric vibratory motor, such as the motor portion of a dynamic loud speaker, and has its moving part connected to the tone arm 42 by a cord or wire 54. The driving motor 52, especially if it is in the form of the motor of a dynamic loud speaker, is responsive to even minor variations in the frequency and amplitude of the energizing current supplied thereto, and for this reason, may be considered as a synchronous vibratory motor.

In order to produce a record having its various sound frequencies modified at a vibrato rate and to a vibrato extent, it is necessary to supply current to the driver 52 at a vibrato frequency and at a voltage determined by the "width" of the vibrato frequency shift which is desired. The means for supplying the energizing current for the driving motor 52 is illustrated in Fig. 1 as comprising a disc 56 having a plurality of notches 57 in its periphery. These notches are not necessarily accurately spaced along the periphery, but on the contrary, are preferably spaced rather irregularly. The disc 56 is driven by an adjustable speed motor 58 (which may include a speed-reducing gearing), and the speed of the motor is adjustable by means of a rheostat 60. Assuming

that the disc 56 has twelve notches 57, as shown, the speed of the disc should preferably be adjustable between 20 and 50 R. P. M. Within this range of adjustment, the notches 57 pass a stationary point at a rate of four notches to ten notches per second.

A suitable continuous light source 62 is located above the disc 56 in position to project rays of light through the notches 57. Beneath the disc 56 is located a shutter 64 mounted in suitable guides 66 and biased to move to a position shutting off the light rays passing through the notches 57, by a pair of tension springs 68. A photocell 70 is positioned beneath the shutter 64 so as to have the amount of light reaching it from the source 62 controlled by that passing through the notches 57 and past the shutter 64. The shutter is adapted to be manually operated by any suitable means, such as a cord 72 attached to it.

The output of the photocell 70 is supplied to a preamplifier 74, the output of which is in turn connected to a low-pass filter 76 and power amplifier 78 and supplied as the energizing current for the driving motor 52. The low-pass filter circuit 76 is preferably made to pass all frequencies below 10 C. P. S. without appreciable attenuation and to cut off all frequencies above this value.

It will be understood that the phototube will be enclosed in a suitable housing so that it will be affected only by the light reaching it through the notches 57 and passing the shutter 64.

In operating the apparatus of Fig. 1, the potentiometer 60 is adjusted to cause the motor 58 to operate at the desired speed, and after placing the record A upon the turntable 32, the needle of the pickup is placed upon the record. The sound recorded on the record will be heard by the operator from the speaker 40, and as a phrase or sentence in the musical selection is reached which lacks vibrato, the operator will pull the cord 72 to operate the shutter 64 to the extent desired. Since the extent of opening of the shutter 64 determines the amplitude of the electrical impulses delivered to the driving motor 52, it will determine the width of the vibrato effect introduced. It will be understood that as the pickup 34 is oscillated by the vibratory driver 52, its speed of motion will be periodically varied, relative to the record A, and due to the Doppler effect, the electrical signal produced in the pickup 34 will periodically vary with respect to the frequency of the sound on the record A being picked up.

This frequency modulated sound is, by means of the recording apparatus 38, recorded on a new record which serves as a master record from which commercial impressions may be made in the well known manner.

Thus, by operating the shutter control cord 72 and the rheostat 60, the operator may control the periodicity of the vibrato modulations introduced and also control the extent or frequency range of the vibrato, and he may introduce the vibrato effect at will during such portions of the music being re-recorded as will enhance the quality of tone and will improve the overall effect of the music upon a listener.

Due to the provision of the low-pass filter 76, extraneous frequencies above the vibrato frequency range are not supplied to the driver 52, thus assuring that its vibrations will be substantially simple harmonic motion. In order to accomplish this result without requiring an excessively powerful driver 52, the mass of the tone arm 42 and parts carried thereby is preferably

so related to the compliance of the supporting members 44 and 46 that the tone arm will have a natural frequency of vibration generally within the vibrato frequency range, i. e., from 4 to 10

5 C. P. S.

The friction of the needle on the record and the damping effect of the sponge rubber support 46 tend to reduce the Q of the vibratory portion of the apparatus so that the tone arm may readily be made to vibrate throughout the range from 4 to 10 C. P. S. without the necessity of utilizing an excessively powerful driver. Furthermore, the friction of the needle on the record and the internal friction of the support 46 are effective rapidly to damp vibration of the tone arm assembly so that the tone arm will quickly come to rest upon discontinuing the supply of energizing electrical impulses to the driving motor 52.

Because of the provision of this low-pass filter 76, the light source 62 may be energized with commercial alternating current.

In so far as the production of music is concerned, the sound emanating from the speaker 40 will be greatly improved as compared with that produced from the record without vibrating the pickup 34, and thus, in its broadest aspects, the improved result of my invention is obtained merely by amplifying and translating into sound the electrical impulses produced in the pickup 34, without re-recording the sound.

The apparatus shown in Fig. 2 is in general principle similar to that shown in Fig. 1, and corresponding parts of the system are therefore designated by the same reference characters as used in connection with Fig. 1, although some of the parts of the system are illustrated in greater detail.

In the system of Fig. 2, the driver 52 is illustrated as comprising a permanent magnet dynamic speaker motor, including a voice coil 80 wound on a form 82 which is connected to a flexible supporting spider 84, the spider being connected by a cord 54 with the resilient support 44 for the tone arm 42. The recording apparatus is illustrated as comprising a recording amplifier 86, the output of which is supplied to the cutter head 88 of the recording apparatus 90, carrying a record blank B upon which the sound as modulated by the vibrato apparatus is to be re-recorded.

The voice coil 80 derives its power from a variable frequency oscillator 92, the frequency of oscillation of which may be varied by a suitable control 94 for manual adjustment of the frequency and the frequency of which may be periodically varied by a periodic frequency shifter 96. Assuming that the variable frequency oscillator is one in which a variable capacity is employed to determine its frequency, the frequency control 94 may comprise merely a variable condenser in parallel with the tuning capacity of the oscillator, while the frequency shifter 96 may comprise an additional variable condenser in shunt with the tuning condenser of the oscillator provided with means for cyclically varying its capacity.

The output of the oscillator is fed to a suitable intensity control device 98 having, in addition to its manually adjustable controlling elements, a variable resistance 100, the moving contact of which is connected to a pivot shaft 102 secured to the frame 48. Thus, as the needle of the pickup 34 approaches the center of the record A and the lineal speed of the record with respect to the pickup needle decreases, the amplitudes of the

impulses delivered by the variable frequency oscillator 92 are correspondingly decreased. The output of the intensity control device 98 is amplified by a power amplifier 104 and supplied to the voice coil 80 of the driver motor.

The variable frequency oscillator 92 is preferably adjustable by the control 94 to oscillate at any desired frequency between 4 and 10 C. P. S., but due to the periodic frequency shifter 96, the vibrato periodicity is not maintained constant, but changes gradually, thus overcoming the musical disadvantage of having the vibrato always at the same periodicity. The provision of the tunable oscillator instead of the photoelectric system of Fig. 1 as a source of electrical impulses for energizing the driving motor 52, results in a reduction in cost of the apparatus without materially interfering with the extent of control which the operator has over the width and frequency of the vibrato modulation.

The apparatus shown in Fig. 3 is generally similar to that of Fig. 2, the corresponding parts bear the same reference characters. The essential difference in the apparatus is that the bracket 48 has an extension 106 carrying a motor 108 (which may include a suitable gear speed reduction), the motor being connected by a belt 110 with a suitable pulley 112. The pulley 112 is provided with a plurality of holes 114 spaced different distances from the center of the pulley, which are adapted to receive a pin 116. The pin 116 has one end of a belt 120 swiveled thereto, the belt passing over an idler pulley 122 and having the other end connected to the tone arm 42 and its support 44. The speed of the motor 108 may be varied by a manually adjustable rheostat 124, while the degree or width of the vibrato effect may be varied by positioning the pin 116 in one of the other holes of the pulley 112.

A further modified form of driving motor for vibrating the tone arm 42 is illustrated in Fig. 4 and is illustrated as comprising a pivotally mounted frame 126 which is generally U-shaped in conformation and has an electromagnet 128 secured thereto, the armature 130 of the electromagnet being connected by a rod 132 with a tensioned member 134 attached to the tone arm 42. The electromagnet 128 is energized from a generator 136 which is driven by a motor 138, the speed of which is controlled by a rheostat 140. The moving contact of the rheostat 140 is connected to a worm wheel 142 so as to move therewith, the worm wheel being rigid with a pin 144 to which the lower end of the tensioned member 134 is connected. The worm wheel is adapted to be rotated in either direction by a manually adjustable worm 146.

Thus, as the speed of the motor 138 is increased by adjustment of the rheostat 140, the tension on the tensioned member 134 is simultaneously increased so that the tone arm 42 and parts moving therewith, together with the tensioned member 134, form a broadly tuned mechanical system, the natural frequency of vibration of which will change with the frequency of the electrical impulses supplied to the electromagnet 128. The impulses from the pickup 34 are supplied to the monitoring speaker and a recording apparatus, in a manner similar to that previously described with respect to Figs. 1, 2, and 3.

The circuit and apparatus of Fig. 5 is generally representative of a suitable form of oscillator with its various controls and power amplifier for use in the system shown in Fig. 2, the circuit and parts of Fig. 5 representing parts 92, 94, 96, 98,

100, 104, and 52, shown diagrammatically in Fig. 2.

The oscillator may comprise a pair of pentodes 150, 151, connected in push-pull with their frequency of oscillation determined by the resonant frequency of a mesh comprising inductance L1 and condensers C1, C2, and C3, the condenser C1 serving as the primary frequency determining condenser, while the condensers C2 and C3 are adapted to be connected in parallel with the condenser C1 by the operation of a switch 152, thereby to vary the frequency of oscillation of the oscillator.

A further means for periodically shifting the frequency of oscillation of the oscillator 150, 151, comprises a reed 154 (having a natural frequency of oscillation in the order of 3 C. P. S.), suitably maintained in vibration by a driving electromagnet 156 in the well known manner, the reed 154 carrying an insulated contact plate 158 which is adapted to complete a circuit through an inductance L2 to connect the latter in parallel with the inductance L1. The periodic frequency shifting circuit may be rendered inoperative by opening a switch 160.

The oscillations generated in the tubes 150, 151 and associated circuits are supplied in push-pull to the grids of triodes 162, 163, which are resistance coupled to amplifier tubes 164, 165, while the latter are coupled through a transformer T1 with a pair of push-pull control tubes 166, 167. The grids of the tubes 166, 167 are normally biased substantially to cut off through a resistor R1 which connects the center tap 169 of the secondary of transformer T1 to a point of fixed negative potential indicated as -50 v., a suitable biasing voltage for the control tubes 166 and 167, assuming that the latter are tubes of the 6K7G type.

The negative bias on the tubes 166, 167 may be decreased by closure of a switch 168 which connects the center tap 169 to a terminal of constant direct current potential, indicated as -5 v. With a potential of -5 volts on the grids of tubes 166, 167, they will transmit the impulses of the oscillator.

Occasionally it is desired to have the music modulated by the vibrato frequency for only a short interval, and to accomplish this purpose, there is provided a key 170 which is adapted to connect a normally charged condenser C4 to the center tap 169, the size of the condenser C4 determining the duration of the interval through which the control tubes will be rendered conductive and hence the interval through which the vibrato modulation (as will hereinafter appear) is effective.

Additional condensers C5 and C6 are adapted to be connected in parallel with the condenser C4 by manual operation of switches 172 and 173, respectively. It will be noted that condenser C4 (as well as condensers C5 and C6, if the switches 172 and 173 are closed) are adapted to be charged from the terminal -5 v. through a resistor R2 when the key 170 is in its undepressed position.

The outputs of the control tubes 166, 167 are resistance capacity coupled in push-pull manner with power amplifier tubes 174, 175. A potentiometer 176 shunts the input of the power amplifier tubes 174 and 175 and is adapted to be operated by a manual control knob 178, the knob being normally biased by a torsion spring 180 to move in a counterclockwise direction to the maximum extent, thereby to cause the complete shunting of the input to the power tubes 174, 175 and

cut off the transmission of the oscillator signals thereto.

Whenever the vibrato effect is desired, the control knob 178 is moved clockwise, thereby to connect a greater or lesser portion of the potentiometer resistance 176 across the input circuits of the tubes 174, 175. Release of the control knob will immediately result in cutting off the signal. The output of the power tubes 174, 175, is coupled through a transformer T2 with the driver motor 52.

In order further to control the amplitude of the signal transmitted to the driver 52 in accordance with the distance of the needle from the center of the record, a potentiometer 182 is connected across the primary of the transformer T2 and, by the position of the sliding contact therefor, determines the amplitude of the energizing signal for the driver 52. The sliding contact of potentiometer 182 may be physically connected to (but electrically insulated from) the pivot shaft of the tone arm carrying frame 48, as shown, for example, in Fig. 2.

The oscillator of Fig. 5 is illustrated as representative of any suitable source of electrical impulses of vibrato frequency in which the frequency may be easily controlled, may be periodically shifted, and in which the amplitude may be controlled in various ways to produce a transitory increase in amplitude of the signal or to produce any desired sustained signal amplitude.

The apparatus shown in Fig. 6 constitutes a simplification of that previously described, including a driver 52, which may be supplied with electrical impulses at vibrato frequencies by any suitable means, previously or hereinafter to be described, the tone arm 42 vibrated by the driver 52 having its pickup cooperable with the record A mounted on the turntable 32, which is detachably secured over the top of a spindle 186, the spindle also carrying a turntable 188 upon which rests the record blank B.

The recording head 88 is supplied with the signal picked up by the pickup 34, amplified by the pre-amplifier and power amplifier 188, which latter also supplies the monitor speaker 40. The spindle 186 is driven at a constant speed through a worm wheel 190 meshing with a driving worm 192.

A further modified form of apparatus is shown in Fig. 7 as comprising a non-vibratory pickup 34 and tone arm 42 cooperating with a record A carried by a turntable 194 which is mounted for oscillation on a rotating shaft 196 driven by a worm 197 and worm wheel 198. A torsion coil spring 200 has one end anchored to the turntable 194 and its other end anchored to the worm wheel 198. The worm wheel 198 has a cam 202 formed thereon, this cam preferably having downwardly extending camming projections spaced somewhat irregularly. For example, assuming that the normal speed of rotation of the turntable 194 is 78.0 R. P. M., five cam projections may be provided on the cam 202 spaced apart angular distances as follows: 68°, 73°, 67°, 78°, and 74°.

A follower roller 204 is cooperable with the cam 202, the roller being carried at the end of a lever 206 pivoted at 208 and biased by an adjustable compression spring 210 to hold the roller 204 in engagement with the cam surface. The lever 206 has an upwardly extending arm 212 carrying a braking shoe 214 of felt, leather, or similar material, the shoe being cooperable with a friction ring 216 secured on the lower surface of the turntable 194.

Thus, as the worm gear 198 rotates, the cam 202 oscillates the lever 206 periodically to bring its brake shoe 214 into momentary engagement with the friction ring 216 and thus momentarily slightly retard the turntable 194. The rotary movement of inertia of the turntable 194 and parts carried thereby is so related to the resilient torque of the spring 200 that the normal frequency of oscillation of the turntable with respect to the constantly rotating shaft 196 will be in the order of 7 C. P. S. Such oscillation is relatively rapidly damped due to the friction imparted by the needle in the groove of the record as well as by the friction at the bearing of the turntable 194 upon its shaft 196.

By turning a thumb screw 218, the effective force of the spring 210 may be varied, thereby to change the contact pressure of the shoe 214 against the friction ring 216, and thus to vary the angular degree of oscillation of the turntable with respect to its shaft 196, with the result that the width of the vibrato effect may be varied.

In the embodiments of the invention shown in Figs. 8 to 12 inclusive, the turntable is resiliently coupled to its worm wheel 220 by a torsion spring 222, and thus the turntable 32 will oscillate relative to the drive shaft 224 whenever the latter is accelerated or retarded.

In Fig. 8, the worm wheel 220 is driven through suitable gearing by a motor 226 which is preferably of the synchronous type energized by current from a variable frequency source 228 which may be, for example, a variable frequency oscillator and amplifier of the general type shown in Fig. 5, and also provided with a frequency shifting apparatus 230. The oscillator may be adjusted to oscillate at a desired mean frequency, such as 6 C. P. S., while the frequency shifting apparatus 230 will operate to vary the frequency generated by the oscillator amplifier 228 between limits above and below 6 C. P. S., such as, for example, 5.5 and 6.5 C. P. S.

The resultant changes in the speed of the driving motor 226 will be reflected in oscillation of the turntable 32 relative to its drive shaft 224, and for this reason, the spring 222 is so chosen that its compliance will be of a value causing the turntable to have a natural frequency of oscillation relative to its drive shaft in the order of 6 C. P. S.

Since the changes in speed of the motor 226 are not very accurately and directly reflected in changes in the speed of movement of the turntable 32, a simplified means for causing such oscillation of the turntable and its shaft may be provided. Such more simplified apparatus is shown in Fig. 9, wherein, the driving motor 232 may be of a type in which the speed varies with impressed voltage and current is supplied through a variable resistance 234, a selected portion of which may be periodically shunted, at a vibrato rate (by a circuit including a switch 236 closed by a cam 238 driven from any suitable mechanism, preferably one which provides means for varying the speed of the cam 238).

In both Figs. 8 and 9, the pickup 34 and tone arm 42 may be of conventional construction and mounted on a pivot in the usual manner.

In Figs. 10, 11, and 12, is disclosed a further modified form of turntable drive by which vibrato oscillations of the turntable relative to its drive shaft may be obtained. In each of these, the turntable is driven by a synchronous or constant speed motor 226, as in the construction of Fig. 8.

In Figs. 10 and 11, the turntable 32a is provided with arcuate segmental flanges 240 projecting

from its periphery. These segmental flanges are preferably spaced irregularly about the turntable and are adapted to pass between the poles of a permanent magnet 242 which is mounted on a slide 244 manually controlled by a pivoted cam 246 which is operated by a handle 248. The slide 244 is biased to move the permanent magnet 242 away from the segmental flanges 240 by a pair of springs 250. The permanent magnet is effective to apply a braking torque to the turntable 32a as the segmental flanges 240 move away from the permanent magnet, while tending to accelerate the turntable as a segmental flange approaches the magnet.

It will be understood, of course, that the turntable flanges 240 are made of soft steel or other magnetic material. In this apparatus, as in those of Figs. 8 and 9, the pickup 34 and tone arm 42 are pivotally mounted in the customary manner.

In Fig. 12, the apparatus is generally the same as that of Figs. 10 and 11 except that an electromagnet 252 held in fixed position has been substituted for the permanent magnet. The turntable 32a may be of the same construction as shown in Figs. 10 and 11, assuming that the electromagnet 252 is energized by direct current. If alternating current is used to energize the electromagnet, the segmental flanges 240 are preferably made of copper or aluminum so as to provide a braking torque due to eddy current losses as the flanges 240 pass between the poles of the electromagnet 252. Whether energized by alternating or direct current, the effectiveness of the electromagnet 32 may be varied by a rheostat 254.

As an alternative construction, the turntable may be provided with a continuous flange passing between the poles of the electromagnet 252, and the electromagnet energized by alternating current of relatively high frequency modulated substantially 100% by a vibrato frequency.

In each of the constructions of Figs. 8 to 12 inclusive, the electrical vibrations produced in the pickup are amplified and supplied to a monitor speaker and a recording apparatus for making a master record of the vibrato modulated sound.

In Fig. 13, is disclosed an apparatus suitable for introducing the vibrato effect in sound on film records. The apparatus comprises a platform 256 which is connected to a fixed support 258 by a leaf spring 260. The platform 256 carries a light source 262 and a lens system 264 for forming the light from the lamp 262 into a narrow beam for scanning a sound record on a film 266, the film being driven at constant speed by any usual means. The beam of light as modulated by the record on the film 266 falls upon a photo cell 268, the output of which is amplified by amplifier 270 and supplied to a monitoring speaker 272 and to a recorder 274. The recorder 274 may be one for recording sound on film or recording it on a phonographic record.

In order to produce a vibrato effect in the sound re-recorded or as it is heard from the monitoring speaker 272, the platform 256 is oscillated by a driver 276 of any suitable construction, such as that previously described, the driver being energized by an oscillator and amplifier 278, which may be of the construction shown in Fig. 5, and having suitable controls for varying the frequency and amplitude of its output, thereby to vary the frequency and amplitude of oscillation of the platform 256.

Since the means for moving the film 266 is sup-

ported independently of the platform 256, the light beam scanning the film will have its motion with respect to the film effectively accelerated and retarded at the speed of oscillation of the platform 256.

The construction shown in Fig. 14 is quite similar to some of the modifications previously described, and corresponding reference characters have therefore been applied to the parts which are identical with those previously described. In this construction, the tone arm 42 is pivotally secured to the upper end of a relatively rigid support 280. The lower portion of the support 280 is imbedded in a cushion 282 made of sponge rubber or the like which is elastic and yet affords sufficient mechanical resistance to oscillation of the support 280 as to damp such oscillation quite rapidly.

Fig. 15 illustrates an apparatus for use in producing sound directly, as for broadcasting purposes, or making a record of sounds from a plurality of sources, in which some sounds are vibrato modulated and others are not. For example, in broadcasting or recording the music produced by a large orchestra, it may be desirable to add a vibrato effect to the music produced by one section of the orchestra, the instruments of which are incapable of producing a vibrato, while it may not be desirable to add a vibrato effect to the music produced by other sections of the orchestra, such as the string section, since the music produced by such section will already contain an ample vibrato.

In Fig. 15, a microphone 290 is provided for picking up sounds to which it is desired to add a vibrato, while a microphone 291 is provided for sounds already containing a vibrato or sounds which would not be improved by the addition of the vibrato effect. The signal picked up by the microphone 290 is amplified by an amplifier 292 and supplied to a recording electromagnet 294 which is cooperable with a hardened steel band 296 secured to the periphery of a circular wheel 298. The wheel 298 is rotated at constant speed by any suitable means. The recording of the sound on the band 296 is accomplished electromagnetically in the manner of the telephone. A magnetic pickup 300 is carried by an arm 302 pivoted on the shaft of the wheel 298, and is adapted to be oscillated about the axis of the wheel by a driver motor 52 energized by current of adjustable frequency and amplitude supplied by an oscillator 92, which may be of the construction shown in Fig. 5.

The signal picked up by the pickup 300 is supplied to an amplifier 304, the output of which is connected to a mixer panel 306. The output of the mixer panel is supplied to a monitor speaker 40 through an amplifier 308 as well as selectively to the modulator and radio frequency amplifier 310 of a radio broadcasting transmitter or to the amplifier 86 of a recorded 88, 90, depending upon the operation of a pair of switches 312, 313. A wiper magnet 314 is fixed beyond the pickup 300 and is effective to erase the signal magnetically recorded on the band 296. Depending upon the position of the pairs of switches 316, 318, the signal picked up by the microphone 291 may be fed either to an amplifier 320 or 322. With the switches 316 and 318 in the position shown in the drawings, the signal is supplied to the amplifier 320 and thence to a recording electromagnet 324 so that the signal from the microphone 291 is recorded on the magnetizable band 296 and may be picked up by a magnetic pickup 326 which

preferably is angularly spaced with respect to the recording magnet 324 the same distance as the average distance between the recording magnet 294 and the pickup 300. Such spacing is desirable so as to avoid any phase displacement or echo effects in the music produced, since the signal picked up by the pickup 326 is supplied to the amplifier 322 and hence to the mixer 306, where the signal is combined with that picked up by the magnetic pickup 300. By adjustment 10 of controls 328 and 329 on the mixer panel 306, the relative amounts of the signals from the pickups 300 and 326 may be readily controlled.

When the switches 316 and 318 are moved into opposite position from that in which they are shown in the drawings, the signal picked up by the microphone 291 is fed directly to the amplifier 322 and thence to the mixer 306. This signal will be slightly ahead (in point of time) of the signal derived from the pickup 300, but in certain circumstances, such lead of one signal over the other is desirable.

Thus, by the use of the apparatus of Fig. 15, multiple sources of sound or music may have a vibrato added thereto or not, as desired, and the sounds recombined into a single composite signal, which may be amplified and recorded, broadcast, or heard through a speaker system.

Fig. 16 discloses a generating system which may be used in place of the apparatus shown in Fig. 5. The generator comprises an oscillator tube 332, which is preferably a gas triode of the 885 type. The oscillator is of the relaxation type, in which a condenser C8 is charged through a timing resistor R1 connected to a suitable source of direct current potential, such as +300 v. The oscillator is oscillated at a frequency determined generally by the values of the condensers C8 and R10, but its frequency may be adjusted by means of a variable self-bias resistor R11. This oscillator is preferably adjusted so as to oscillate at a frequency of approximately 6 C. P. S. The bias on the tube 332 is determined not only by the self-bias resistor R11, but also by the potential of a terminal 334, which is connected to the grid of the tube 332 by a protective resistor R12.

The potential at the terminal 334 varies periodically at a frequency of approximately 1 C. P. S. due to its connection through a blocking condenser C9 and filtering resistor R14 with the output circuit of an oscillator tube 336, which may likewise be a gas triode of the 885 type. The oscillator, including the tube 336, may be of the same construction as that including the tube 332 except for the values of the circuit constants, these being so chosen as to cause the oscillator tube 336 to operate at a frequency of approximately 1 C. P. S. The output of a relaxation oscillator of the type illustrated is of generally saw-tooth wave shape, and to change this output wave into one more nearly sinusoidal, the filtering resistor, together with a condenser C10, forms a mesh, most effective to transmit frequencies in the order of 1 C. P. S.

The terminal 334 is connected to ground through a grid resistor R16 of relatively high value. The resistors R16 and R12 determine the normal bias, in effect forming a variable bias determining network for the tube 332, the fixed adjustable bias being controlled by the variable resistor R11.

As a result of the one-cycle variation in grid bias on the oscillator tube 332, its frequency of oscillation will vary each second through frequencies between 5.5 and 6.5 C. P. S. The output

signal of the oscillator tube 332 is of saw-tooth wave shape and in order to change the wave shape to one substantially sinusoidal, filtering resistors R18, R19, and condensers C12 and C13 are provided in the output circuit, which is coupled to the input circuit of an amplifier tube 340 by a blocking condenser C14. The primary of a transformer T1, corresponding to the correspondingly numbered transformer of Fig. 5, is connected in the plate circuit of the amplifier tube 340. The output circuit beyond the transformer T1 may be identical with that shown in Fig. 5.

It will thus be seen that by the use of the circuit of Fig. 16 impulses continuously varying in frequency between 5.5 and 6.5 C. P. S. (or comparable values) may be supplied for the operation of the driving motor used to vibrate the pickups 34 or other elements to be vibrated at a vibrato rate which are employed in the various modified forms of the invention.

Another form of vibrato frequency generating system is shown in Fig. 17, in which a random noise generator 342, which may be of any suitable form, such as an electrical signal derived from a 25 random noise phonograph record, or may be the electrical equivalent of noises, such as the breaking of ocean waves, the crackling of a fire, or the electronic "noises" of an unexcited vacuum tube circuit, etc.

30 The output of the noise generator 342 has its amplitude controlled by an attenuator 344, and is supplied to a filtering apparatus 346, which may include a tunable inductive reactance filtering mesh 348, which is tuned to pass frequencies in 35 the order of 6 C. P. S. The frequency passed by the filtering apparatus 346 may be controlled by a periodic frequency changer 350 connected to vary the resonance peak of the filtering mesh 348. The output of the filtering apparatus 346 is supplied to 40 a power amplifier 352 and the amplified impulses utilized to energize the vibratory driver 52 utilized in the various forms of the invention.

Because of the random character of the original frequencies supplied by the generator 342, the output 45 of the amplifier 332 will vary in frequency throughout a limited range (depending upon the sharpness of the resonance peak of the filtering mesh 348), and as a result, a vibrato determined by this output frequency will be very irregular and 50 not be recognized as a periodic variation in the frequency, but instead, will be heard as a fullness and richness of the tone produced.

The apparatus illustrated in Fig. 18 is designed for direct recording of a vibratoless sound in a 55 manner such that the recorded sound will contain the vibrato. In this figure, the sound is picked up by a microphone 354 and amplified by an amplifier 356 and supplied to a monitoring speaker 40, as well as to the cutter head 358 of a 60 recording apparatus. The cutting head is vibrated by means of a power driver 52 supplied with impulses of a varying vibrato frequency, as might be obtained from the photoelectric pulse generator 360 (as shown in Fig. 1). It is, of course, essential 65 that the pulse generator 360 is provided with sufficient amplification that the driver 52 may be vibrated smoothly so as to not cause distortion in the record sound due to irregularities in the resistance to movement relative to the record offered 70 by the cutting stylus of the head 358. Thus, the original master record of a musical production could be made to incorporate a vibrato not present in the music as produced.

Generally speaking, a vibrato effect is more desirable in tones in the higher frequency range

than in the low frequency, especially bass, ranges. In order to make it possible to "dub" a record from a record of music not containing sufficient vibrato, and have the vibrato appear only in the middle and higher ranges, the apparatus shown in Fig. 19 may be employed. In this apparatus, a pair of turntables 32 are secured to a common shaft 362 driven by a suitable motor mechanism 364. The pickups 34a and 34b carried by tone arms 42a and 42b cooperate respectively with the 10 two records A, and each of the tone arms is adapted to be vibrated in any one of the numerous ways previously described. The operation of the vibrating mechanisms for the two tone arms is preferably independent and independently controllable.

The signal picked up by the pickup 34a is supplied to a filtering mesh 366, while that derived from the pickup 34b is supplied to a filtering mesh 367. The filtering mesh 366 is a high-pass filter, 20 sharply cutting off all frequencies below 250 C. P. S., while the filter 367 is a low-pass filter, sharply cutting off all frequencies above 250 C. P. S. The output of the filters 366 and 367 is supplied to a mixer 368 having controls 370 and 371, by which the relative amplitudes of the signals from the filters may be regulated and the combined output of the filters supplied to an amplifier 372. The signal from the amplifier 372 is supplied to the cutting head of a recorder 374.

In operating the apparatus of Fig. 19, two identical records are placed upon the turntable, (the shaft 362 is sectionalized to permit the insertion of the lower record), the records being so placed on their turntables that the sound tracks thereon start at the same angular position. The needles of the pickups 34 having been placed in the corresponding grooves of the two records, the re-recording may be commenced, the operator controlling the frequency and extent of vibration of the pickup 34a to produce the most desirable musical result. Such introduction of vibrato, due to the filter 366, will be effective substantially exclusively upon frequencies above 250 C. P. S. Ordinarily, the vibrating mechanism for the pickup 34b will not be energized, but in the event that for special musical purposes a vibrato is desired on the frequencies below 250 C. P. S., the vibrating driver for the pickup 34b may be energized, and in such instances that both pickups 34a and 34b are vibrated, they are preferably vibrated at slightly different frequencies and usually with the vibration of the pickup 34b of less amplitude than that of the pickup 34a.

In Fig. 20 is illustrated a very simple form of apparatus for introducing a vibrato effect in sound being re-recorded. In this figure, the tone arm 42 is mounted upon a flexible resilient support 380 imbedded in a sponge rubber cushion 382. A flexible band or tape 384, such as a cloth ribbon, has one end secured to the tone arm 42 and its other end anchored to a base 386. The upper surface of the base 386 has a layer 388 of felt or the like.

The output of the pickup 34 is supplied, as in most of the previously described forms of the invention, to an amplifier 36, monitoring speaker 40, and a recording apparatus 86, 90. Whenever, in the re-recording of a musical selection from the record A, it is desired to introduce the vibrato effect, the operator will merely press upon the band 384 periodically at a vibrato frequency rate, thereby vibrating the pickup 34 and tone arm 42.

By moving his finger downwardly toward the 78

anchored end of the tape 384, the operator may very readily control the amplitude of the vibration imparted to the pickup 34, whereas, when the band 384 is engaged toward the center thereof, the amplitude of the vibration, for a given finger pressure, will be at a maximum. The apparatus of Fig. 20 thus forms a very simple and effective means for vibrating the pickup to cause introduction of the vibrato effect in the music being re-recorded.

In the various forms of vibrato introducing apparatus disclosed herein, it will be apparent that the vibrato modulated sound may be listened to directly from speakers, may be transmitted to a radio broadcast transmitter, or may be re-recorded upon a master record, from which other commercial records may be produced. The apparatus is principally designed for the manufacture of records of improved musical characteristics due to the artistic introduction of the vibrato effect. As previously indicated, the degree of the skill of the operator of the apparatus will, in a considerable measure, determine the effectiveness of the method of making the vibrato modulated sound records. However, even a relatively unskilled operator, with the simple form of apparatus disclosed herein, will be able very materially to improve the musical attractiveness of recorded sound, provided he adheres to the relatively simple principles involved. The vibrato effect should preferably be employed intermittently in the appropriate portions of the musical selection for the purpose of introducing richness and fullness in the tones and variety in the overall musical effect.

While I have shown and described a number of different forms of my invention and a number of different methods by which the desired results of the invention may be obtained, it will be apparent to those skilled in the art that other modifications and variations of the apparatus and method may be made without departing from the underlying principles of the invention. I therefore desire, by the following claims, to include within the scope of my invention, all such modifications and variations by which substantially the results of my invention may be obtained by the use of substantially the same or equivalent apparatus and methods.

I claim:

1. The method of recording sound upon a record by a recording means supplied with the sound as electrical impulses which includes the step of relatively moving the recording means and record at a speed represented by a constant speed modified by acceleration and retardation at a periodicity in the order of 7 C. P. S. and to an extent such that the maximum and minimum relative speeds will be between 1% and 3.0% above and below the normal speed respectively.

2. The method of making a sound record which comprises, translating mechanical sound vibrations into electrical impulses while modulating the electrical impulses at a vibrato rate and to the extent of a musical vibrato, and making a record of the modulated electrical impulses.

3. In a sound recording apparatus, the combination of a first sound record, means to move said record at a constant speed, a pickup cooperable with said first record for translating the sound vibrations recorded thereon into electrical impulses, a compliant support for said pickup, a driving motor for vibrating said pickup in the direction of the constant speed relative movement between the pickup and first record, means

associated with said motor for varying the speed and amplitude of vibrations transmitted from said motor to said pickup, and means for producing a second sound record of the electrical impulses generated by said pickup.

4. In a sound recording apparatus, the combination of a sound record, a pickup cooperable therewith, means for relatively moving said record and pickup at a constant speed, means for superimposing upon said constant speed motion an oscillatory motion, a vibratory motor for supplying said oscillatory motion, a source of light, a photoelectric cell, an adjustable speed light interrupter between said source and said cell and operable to interrupt the passage of light therebetween at a vibrato periodicity, a manually operable variable opening shutter between said source and said cell, means to amplify the electrical impulses produced in said cell, and means for transmitting the amplified impulses to said vibratory motor to energize the latter.

5. In a sound recording apparatus, the combination of an acousti-electric translating means, an amplifier for the electrical signals produced thereby, a sound recording means connected to said amplifier, a record blank to be operated upon by said recording means, means for relatively moving said recording means and record blank at a constant speed, and means for imparting to said recording means and record blank an additional component of relative motion comprising alternate acceleration and retardation at a periodicity in the order of 7 C. P. S.

6. In an apparatus of the class described, the combination of a strip film having a sound track thereon, means for moving said film at a constant speed, a photoelectric system for scanning the sound track on said film and translating the variations thereof into an electrical signal, means for vibrating the scanning portion of said system in a direction generally parallel to the direction of movement of said film, said vibrating means operating at a controllable frequency in the order of 7 C. P. S., and means for amplifying and utilizing the electrical signal produced by said photoelectric system.

7. In an apparatus of the class described, a first means to receive an eradicable record of sound, means for moving said first means at a constant speed, means to impress a record of sound upon said first means, a device to pick up said sound record and translate said record into an electrical signal, a vibratory motor operating at a frequency in the order of 7 C. P. S. connected to vibrate said device along the path of movement of said first means, means for amplifying and utilizing the electrical signal produced by said device, and means for eradicating the sound record from said first means after it has moved past said device.

8. The method of improving polyphonic music which comprises translating the musical sounds into two channels of electrical impulses, modulating the electrical impulses flowing through one of the channels at a vibrato periodicity and to a vibrato extent, mixing the electrical impulses of the two channels, and making a record of the combined electrical impulses.

9. In an apparatus of the class described, the combination of a plurality of identical sound records, a pickup for each of said records, means for moving said records in synchronism, means for moving one of said pickups with respect to its record at a vibrato periodicity, a frequency responsive filter connected to at least one of said

pickups materially to attenuate certain frequencies in the signal derived from its pickup, means for selectively mixing the signals from said pickups, and means for amplifying and utilizing the resulting combined signal.

10. In apparatus of the class described, the combination of a phonograph turntable and pickup, motor means for driving said turntable, a resilient mechanical drive coupling between said motor means and said turntable, the compliance of said coupling being so related to the rotary moment of inertia of said turntable and parts moving therewith that said turntable will have a natural frequency of oscillation in the order of 7 C. P. S. with respect to said motor means, and means for causing said motor means to be accelerated and retarded cyclically at a frequency in the order of 7 C. P. S.

11. The combination set forth in claim 10, in which said motor means comprises a synchronous motor, and in which the means for causing the motor means to be accelerated and retarded cyclically comprises a varying frequency source of electrical energy for said synchronous motor.

12. In an apparatus of the class described, the combination of a phonograph turntable and pickup, motor means for driving said turntable, a resilient driving connection between said motor means and said turntable, and means for intermittently applying a braking torque to said turntable at a periodicity in the order of 7 C. P. S.

13. The combination set forth in claim 12, in which said braking torque applying means comprises a mechanical brake cooperable with said turntable to retard the latter, and means driven by said motor means for operating said brake.

14. The method of improving a musical tone lacking vibrato which comprises modulating the tone frequency by means of a frequency in the order of 6 C. P. S. which is modulated by a frequency in the order of 1.5 C. P. S.

15. The method improving musical tones which comprises modulating the tones by a frequency varying cyclically between frequencies of the orders of 5.5 and 6.5 C. P. S. at a periodicity of the order of 1 C. P. S.

16. In a sound apparatus, a phonograph record, a turntable therefor, a motor for rotating said turntable, a resilient driving connection between said motor and turntable, the compliance of said spring connection being related to the rotary moment of inertia of said turntable and parts rotating therewith that said turntable will have a natural frequency of oscillation in the order of 7 C. P. S., and means for varying the effective driving torque of said motor at approximately said natural frequency of oscillation.

17. In apparatus of the class described, the combination of a phonograph record, means for rotating said record at a constant speed, a pickup cooperable with said record, a resilient support for said pickup, a flexible tape having one end thereof connected to said pickup, and a panel forming an anchorage for the other end of said tape, said tape and panel diverging at an acute angle, whereby intermittent manual pressure on said tape will cause corresponding oscillation of said pickup and result in frequency modulation of the signal produced by said pickup.

18. In apparatus of the class described, the combination of a sound record, means for moving said record at a constant speed, a pickup cooperable with said record, a resilient support for said pickup, a flexible member having one end secured to said pickup, and a fixed anchorage for

the other end of said flexible member, whereby intermittent manual pressure on said member will cause corresponding oscillation of said pickup and result in frequency modulation of the signal produced by said pickup.

19. In an apparatus of the class described, the combination of a sound record receiving member, means for moving said member at a constant speed, a plurality of microphones, recording means cooperating with said member and receiving signals from said microphones, respectively, for impressing separate sound records upon said member, a pair of pickup devices spaced from said recording means in the direction of movement of said member, manually controllable means for oscillating one of said pickup devices in the direction of movement of said member at a frequency in the order of 6 C. P. S., an adjustable mixer for combining the signals produced by said pickup devices, and means for utilizing the mixed signal.

20. The combination set forth in claim 19 in which said member comprises an endless telephone tape, in which said recording means comprises electromagnetic means for elementally magnetizing said tape and in which said pickups are responsive to the elemental magnetization of said tape.

21. The combination set forth in claim 19 in which the means for utilizing the combined signal from said mixer comprises a phonographic recording apparatus.

22. The combination set forth in claim 19 in which the means for oscillating said pickup comprises an electromagnetic reciprocatory driving motor, and an adjustable frequency and adjustable amplitude oscillator connected to supply energizing current to said motor.

23. In combination, a random noise generator, a filtering mesh coupled thereto, said mesh effectively passing frequencies in the vibrato range, a musical tone frequency generating system, and means for frequency modulating the output of said generating system by the output of said filtering mesh.

24. In an apparatus for introducing a vibrato effect into an original musical signal, the combination of means for producing a temporary moving wave pattern representing the original signal, a device for picking up the wave pattern from said means, and means in effect causing oscillatory relative motion between said pickup device and said moving wave pattern producing means at a rate in the order of 6 C. P. S., whereby the signal picked up by said device will be the original signal phase modulated at the oscillating frequency.

25. In an apparatus for introducing a vibrato effect into an original musical signal, the combination of means for producing a temporary moving wave pattern representing the original signal, a device for picking up the wave pattern from said means, means causing oscillatory relative motion between said pickup device and said moving wave pattern producing means comprising a motor, and means electrically generating random oscillations whose average frequencies are in the order of 6 C. P. S., said last named means being connected to said motor to cause the latter to execute corresponding oscillations, whereby the signal picked up by said device will be the

original signal phase modulated by said random oscillation frequencies.

26. In an apparatus for introducing a vibrato effect into music which is in the form of an electrical signal, a magnetizable record, means for magnetically recording said signal on said magnetizable record, a magnetic pickup cooperable with said record, an output system including an amplifier and electro-acoustic translating means coupled to said pickup, means for moving said record with respect to said recording means and said pickup in a direction such that the record passes the recording means and then the pickup, and means for imposing additional relative oscillatory movement of said pickup and said record, said latter relative movement being of a frequency in the order of 7 C. P. S. and of amplitude sufficient to impart a pleasing vibrato effect to the music produced by said electro-acoustic translating means.

27. In an apparatus for introducing a vibrato effect into music which is in the form of an electrical signal, a magnetizable record, means for magnetically recording said signal on said magnetizable record, a magnetic pickup cooperable with said record, means for moving said record with respect to said recording means and said pickup in a direction such that the record passes the recording means and then the pickup, and means for imposing additional relative oscillatory movement of said pickup and said record, said latter relative movement being of a frequency in the order of 7 C. P. S. and of amplitude sufficient to impart a pleasing vibrato effect to the music.

28. In an apparatus for introducing a vibrato effect into music which is in the form of an electrical signal, a magnetizable record, means for magnetically recording said signal on said magnetizable record, magnetic pickup means cooperable with said record, means for relatively moving said record and one of said means at a constant speed, means for relatively moving said record and the other of said means at said constant speed with an additional superimposed oscillatory motion of a frequency in the order of 7 C. P. S. and of an amplitude sufficient to introduce a musical vibrato in the musical signal appearing in said pickup, and a signal utilization means coupled to said pickup.

29. An apparatus for producing music having a vibrato, the combination of a polyphonic instrumentality the output of which comprises an electrical signal which may include a large number of different frequencies many of which are not harmonically related, a unitary vibrato means coupled to said instrumentality for introducing a vibrato effect in the frequencies contained in the output signal thereof, said unitary vibrato means comprising time-delay means, an electrical pickup coupled to said time-delay means, and means for periodically varying the length of the time-delay produced by said time-delay means at a vibrato periodicity in the order of 7 C. P. S., the extent of the variation in time delay being sufficient to produce frequency changes between 0.1% to 3.0% above and 0.1% to 3.0% below the frequencies present in the output signal of the polyphonic instrumentality, and signal utilization means coupled to said pickup.

JOHN M. HANERT.
